COMB

Wesley G. Van Every, Jr., 1409 Krameria St., and A. E. Smith, 1407 Krameria St., both of Denver, Colo.

Filed Oct. 2, 1964, Ser. No. 82,009

Term of patent 14 years

(Cl. D86—8)

FIG. 1.

FIG. 2.

FIG. 3.

FIG. 1 is a side elevation of a comb embodying our new design;

FIG. 2 is an end elevation of the comb of FIG. 1; and FIG. 3 is a top plan view of the comb of FIG. 1.

A rear view of the comb of FIG. 1 is similar but complementary to FIG. 1, while an end elevation opposite that of FIG. 2 is similar to FIG. 2, except that the handle shows as an oblique, planar surface.

We claim:

The ornamental design for a comb, as shown and described.
